(57) **CLAIM**

The ornamental design for a boot as shown and described.

DESCRIPTION

FIG. 1 is a top perspective view showing a top side, a front side, and a right side of a boot in accordance with this invention.

FIG. 2 is a bottom perspective view of the boot of FIG. 1 showing a bottom side, a left side, and a rear side thereof. FIG. 3 is a front elevational view of the boot of FIG. 1 showing the front side thereof.

FIG. 4 is a rear elevational view of the boot of FIG. 1 showing the rear side thereof.

FIG. 5 is a right elevational view of the boot of FIG. 1 showing the right side thereof.

FIG. 6 is a left elevational view of the boot of FIG. 1 showing the left side thereof.

FIG. 7 is a top plan view of the boot of FIG. 1 showing the top side thereof; and,

FIG. 8 is a bottom plan view of the boot of FIG. 1 showing the bottom side thereof.

In the drawings, the broken lines represent environmental structure forming no part of the claimed design.

1 Claim, 8 Drawing Sheets
